UNITED STATES PATENT OFFICE.

GEORGE B. CONREY, OF PHILADELPHIA, PENNSYLVANIA.

SWITCH-OPERATING MECHANISM.

SPECIFICATION forming part of Letters Patent No. 651,564, dated June 12, 1900.

Application filed April 4, 1900. Serial No. 11,428. (No model.)

To all whom it may concern:

Be it known that I, GEORGE B. CONREY, a citizen of the United States, residing at Philadelphia, in the county of Philadelphia and State of Pennsylvania, have invented certain new and useful Improvements in Switch-Operating Mechanism, of which the following is a specification.

My invention relates to switch-operating mechanism for cars, and is designed more particularly for use upon street-cars.

One object of the invention is to provide a positive switching-machine under convenient control of the motorman that shall open a normally-closed switch upon the main line to switch the car to a branch line, this operation to be performed automatically, with the car moving at any desired speed.

A further object is to accomplish this result with the car going in either direction and with branch lines diverging from the main track upon either side.

A further object is to provide a simple and inexpensive mechanism of few parts and inexpensive construction and that shall be adaptable to cars of present construction.

In the drawings, Figure 1 is a longitudinal vertical section of a car, showing the switching mechanism as applied to one side of a car. Fig. 2 is a plan view showing the cable and bell-crank levers connected therewith for operating the switch-lever. Fig. 3 is a top plan view of a portion of the main and branch tracks, showing the switch-point, the spring 35 for automatically closing the switch to provide for a continuous main line, and the supplemental bar and its connection with the switch-point, whereby the switch-point is actuated to close the main line and open the branch line when the switch-lever contacts therewith. Fig. 4 is a perspective view of the bell-crank lever and the switch-operating lever, this view also showing the connection of cable with the bell-crank lever.

As the mechanism is the same on both sides of the car, I have deemed it sufficient to illustrate and describe the arrangement upon one side of the car only.

1 designates the car, upon the under side 50 of which are secured, upon each side of the front and rear axle, respectively, hangers 2, upon which are pivotally secured switch-le-

vers 3, each lever being curved from its pivotal point 4 and having a recessed lower end 5 to receive the tongue 6 of an oppositely curved lever 7, the upper end of lever 7 having a slot 8, through which is passed a pin 9, projecting from a hanger 10, also secured upon the bottom of the car. The lower curved ends of levers 3 and 7 are secured together pivotally by means of a pin 11, which passes through the jaws of the recess and the tongue, respectively.

12 designates a bell-crank lever, one being arranged at each end of the car, upon the under side thereof, and pivotally secured by a bolt 13, so that the lever may move horizontally upon the bottom of the car. The inner end of the bell-crank lever is bifurcated at 14 to receive a grooved idler-wheel 15, secured by a pin 16, the opposite end 17 being passed through a slot 18, formed in the upper end of switch-lever 3, whereby when the bell-crank lever 12 is moved to urge the inner end toward the front of the car the end 17 will move 75 the upper end of the switch-lever 3 in an opposite direction, and thereby depress the lower end of the lever, and by the articulation with lever 7 depress said lever coincidently.

Bell-crank levers 12 are actuated by means 80 of a cable, chain, or rope 19, secured at each end to foot-levers 20, pivoted at the front and rear end of the car, respectively, and angled to put the cable in tension when depressed. In practice I prefer to employ a cable, to which 85 are connected centrally of its length threaded rods 21, upon which to run a turnbuckle 22, by which to adjust to the proper tension cable 19, which is reeved around grooved pulleys 23, secured upon the bottom of the car at proper 90 distances apart to allow the cable to loop in its passage around the grooved wheel 15 in the inner end of the bell-crank lever.

By the arrangement described when one of the foot-levers is depressed it puts the cable 95 into tension by reason of its pulling against the opposite foot-lever, and thereby swings the bell-crank levers at both ends of the car upon their pivots, thereby depressing levers 3 and 7 to operate the switch. When pressure is relieved from the foot-lever, the switch-levers 3 are immediately raised by being 100 swung in a reverse direction upon their pivots by means of a spiral spring 24, connected

- at one end with the car and at the opposite end to the outer end 17 of the bell-crank lever, said spring having been put in tension by the action of the cable. This movement of the switch-levers 3 also raises the levers 7, slot 8 allowing a movement upon pin 9.
- 25 designates the rail of the main track, and 26 the diverging track, the switch-point 27 being pivotally connected in the usual manner.
- 10 To the underside of the switch-point is connected a plate 28, and to said plate is pivotally connected a bar 29, which extends at a slight angle to the rail some distance forward of the switch-point and is pivotally secured 15 to one of the cross-ties, whereby when the car approaches the switch the motorman by depressing the foot-lever throws the switch-levers down in position to contact with bar 29, and thereby throws the point of the switch- 20 point to open the switch from the main line to the diverging line, pressure being relieved from the foot-lever as soon as the car has passed, and the switch-levers return to their raised positions by the action of springs 24.
- 25 In order to firmly secure foot-lever 20 in position to resist a pull from the front lever and to guard against the possibility of a passenger upon the rear platform accidentally or otherwise moving the lever forward, I may 30 provide a cuneal lock 34, which when dropped into the slot in the platform securely locks the lever.
- In order to always maintain an open main line, the switch-point is returned to its original position as soon as the car has passed by means of a spring 30, bearing at one end against a plate 31, secured upon one of the cross-ties, and at its opposite end against the end of bar 29, pivoted at 33, the spring being 35 coiled around a rod 32, secured at one end in bar 29, the opposite end passing through a perforation in plate 31. It will be seen that by this arrangement the car can travel in either direction and the switch mechanism be 40 operated from either end of the car by simply depressing the foot-lever upon the front end of the car and that the mechanism is of convenient attachment to the car without great expense by reason of the simplicity of its parts.
- 45 The arrangement described is adaptable for cars of ordinary length, in which the aggregate length of the bar 29 and the switch-point 27 is sufficient to span the distance intervening between the wheel of the forward truck 50 and the switch-levers upon the rear truck, so that the rear switch-lever contacts with bar 29 to hold the switch-point open for the passage of the wheels of the rear truck before the spring 30 has closed the switch. It will 55 be apparent that in cars of extraordinary 60

length, in which the trucks are separated more than a usual distance apart, the bar 29 may be of greater length than that of the cars of ordinary length, or, if necessary, the rear wheel of the forward truck and the front 65 wheel of the rear truck may be equipped with the oppositely-curved switch-levers in the same manner as heretofore described and operated by duplicated bell-crank levers 12, a simple duplication of the mechanism, as will 70 be readily understood.

What I claim is—

1. In a switch-operating mechanism, oppositely-curved switch-levers pivotally connected at their free ends, one of the levers being centrally pivoted, a foot-lever upon each 75 end of the car, a cable connecting the two, and mechanism connected with the cable and switch-levers, to move the same upon their pivots to depress the curved ends. 80

2. In a switch-operating mechanism, a plurality of switch-levers arranged in parallel relation with the car-wheels and pivoted intermediate their lengths, horizontally-arranged bell-crank levers pivotally connected with the 85 car, foot-levers upon each end of the car, connections with the foot-levers and bell-crank levers, to move the same upon their pivots and connections with the bell-crank levers and switch-levers. 90

3. In a switch-operating mechanism in combination with a car, hangers depending therefrom, a curved switch-lever pivotally suspended upon one of the hangers a curved lever pivotally connected with the switch-lever 95 and movably connected with the opposite hanger, and means for moving the switch-lever upon its pivot upon the hanger, and the curved lever vertically upon the opposite hanger. 100

4. In a switch-operating mechanism, in combination with a car, hangers depending therefrom, a curved switch-lever pivotally suspended upon one of the hangers, a curved lever pivotally connected with the switch-lever 105 and having a slot in its upper end, a pin secured in the opposite hanger and passing through the slot, a bell-crank lever, pivoted to move at right angles to the switch-lever, and connected with the upper end thereof, 110 and means for swinging the bell-crank lever upon its pivot, and thereby the switch-lever pivotally, and the curved lever vertically.

In testimony whereof I affix my signature in presence of two witnesses.

GEORGE B. CONREY.
